STOCK-FEEDING MECHANISM

William B. Retz, Plainville, Conn., assignor to
The New Britain Machine Company, New
Britain, Conn., a corporation of Connecticut

Application February 9, 1951, Serial No. 210,133

9 Claims. (Cl. 29—93)

1

My invention relates to an automatic stock-feeding mechanism for bar machines or the like, and is in the nature of an improvement over U. S. Patent No. 2,555,753 to Donald H. Montgomery, and over my co-pending application, Serial No. 189,727, filed October 12, 1950, now Patent No. 2,656,859 issued October 27, 1953.

It is an object of the invention to provide an improved device of the character indicated.

It is another object to provide an improved means for guiding long lengths of stock in a stock-feeding mechanism of the character indicated.

It is a specific object to provide means for guarding against undue stock whip in a stock-feeding mechanism involving high-speed rotation of the stock.

It is another specific object to provide guide means for confining rotating stock to its axis of rotation, said guide means being effective to guide an otherwise unsupported central part of the stock span for a maximum fraction of the time during which said span exists in a longitudinal feeding of the stock.

Other objects and various further features of the invention will become apparent to those skilled in the art from a reading of the following specification in conjunction with the accompanying drawings. In said drawings, which show, for illustrative purposes only, preferred forms of the invention—

Fig. 1 is a simplified view in elevation of a stock-feeding mechanism of the type disclosed in the above-mentioned co-pending patent applications and shown incorporating features of the invention and for application to a bar machine such as an automatic lathe;

Fig. 2 is an enlarged fragmentary view in partial section of cooperating parts of the invention;

Fig. 3 is a plan view in partial section of the parts shown in Fig. 2;

Fig. 4 is a sectional view taken more or less in the plane 4—4 of Fig. 2; and

Fig. 5 is a fragmentary view similar to Fig. 2, but showing a modified form of the invention.

Briefly stated, my invention contemplates an improved means for guiding, and for automatically maintaining alignment of, the generally central, otherwise unsupported length or span of a piece of stock being fed in a stock-feeding mechanism of the general type disclosed in the above-mentioned copending patent application. As long as the unconsumed, and otherwise unsupported, span of stock is substantial, my alignment means may remain elevated and thus per-

form its function of effectively locating the entire length of stock so as to guard against whip resulting from a high speed of rotation; but upon substantial consumption of the stock and as the danger of whip ceases, my mechanism may automatically retract out of the path of the pusher mechanism, if required.

Referring to the drawings, stock-feeding mechanisms of the character indicated are particularly adapted for internal feeding (from the rear) of the bar machines, such as a lathe 10, having a spindle chuck 11, in which an elongated bar 12 or other piece of stock is to be held. The stock-feeding mechanism may include a frame or I-beam member 13, supported by pedestals 14, and carrying fixed elongated guide means in the form of rails 15 attached to opposite sides of the lower flange of the I-beam. The stock-pusher means may include guide means in the form of rollers 16 on forward and rear carriages 17—18 for guided movement along the elongated rails 15. The pusher means may further comprise an elongated bar 19, guided in both carriages 17—18 and supporting a pusher head 20 at the forward end and on a stock-feeding axis. The pusher head 20 may be revolvably mounted so that the rear end of the piece of stock may be constantly supported for proper alignment with the spindle as the machine 10 performs its operations. The pusher means may be driven by a fluid-pressure means 21 actuating a rack 22 and pinion 23 to advance a sprocket chain 24, all as more fully described in my said co-pending application. Before becoming fully supported by the spindle chuck 11 and the pusher nose 20, a piece of stock may be held in generally the desired orientation by a frame member, such as a longitudinal channel or angle member 9, as will be understood.

In order to accommodate maximum lengths of stock, a substantial length of the pusher bar 19 may be extended substantially fully beyond the rear end of the mechanism, as shown in Fig. 1, and, in order that the last usable length of stock 45 may be consumed in the machine 10, a substantial length of the pusher bar 19 may be extended forwardly of the front end of the stock-feeding mechanism. Selective mechanisms may interconnect the frame, the carriages 17—18, and the pusher means 19—20 for assuring a maximum spacing of carriages 17—18 consistent with the instantaneous longitudinal location of the pusher bar 19, all as more fully explained in my said co-pending application.

55 In accordance with the invention, I provide

automatically retractable and automatically elevated projecting means for the guided support of an otherwise unsupported generally central span of the stock 12 while said span is of such substantial length as to be otherwise subject to whipping or other undesirable functioning during rotation of the machine spindle. Such stock-guide means may be supported for guided movement along the elongated guide means 15 and connected to part of the pusher mechanism so as to maintain a given spacing forward of the pusher mechanism as long as the otherwise unsupported span of the stock 12 is substantial, there being a releasable connection between such stock-guide means and the pusher means when the stock-guide means has reached the forward end of the elongated guide means. However, in the forms shown, I employ a member longitudinally fixedly related to the frame. Such member may be pivotally supported and arranged, when in a projected or stock-guiding position, to yield as the pusher mechanism approaches and to retract out of the path of the pusher mechanism as the stock becomes consumed to a point beyond which the unsupported central part of the span 25 is insubstantial.

In the forms shown, a spring-toggle mechanism is automatically actuated to project the stock-guide means into a stock-guiding position in response to a pusher movement during one part of the pusher cycle, and this toggle mechanism is actuatable to a position holding the stock-guide means in a retracted position in response to a movement of the pusher means during another part of its cycle. Referring more particularly to Figs. 1 to 4 of the drawings, my stock-guiding member is in the nature of a fork 25, pivotally supported on a pin 26, extending between the spaced rail members 15 forming the fixed elongated guide means. The stock-guide member 25 may support a plurality of spaced abutments 27-27' about the stock-guiding axis 28, the abutments 27 being shown diametrically opposed about said axis (28), when in a projected or stock-guiding position, as shown in Figs. 2, 3, and 4; the abutment 27-27' may be said to be angularly spaced about axis 28 over an arc not substantially exceeding a semicircle, said arc being between the axis of pivot 26 and the stock axis 28 and symmetrical about the plane 50 normal to the axis pivot 26 and through axis 28. In the form shown, each of the rails 15 is partly cut away beneath the lower flange 29 of the frame member 13, as at 30, to permit retraction of the guide member 25 to a generally horizontal position, as indicated by the phantom outline 31 in Fig. 2; when fork 25 is projected, an abutment 30' (Fig. 2), which may be a part of the cut-out rail 15, may determine the down position. For actuating purposes, the stock-guide member may be connected to or formed integral with an upwardly extending crank or arm 32. I prefer to employ resilient means for holding the stock-guide member 25 in one of its two possible positions, and in the form shown I employ a toggle mechanism, of which the arm 32 may form a part. The other part of the toggle may include a spring 33 compressionally urged between the free end of the arm 32 and a part of the frame, such as the flange 34 of the frame member 13. In the form shown, the spring 33 is located by a rod 35, urged against a pin 36 on arm 32, and guided by a bushing 37, which, in turn, is located in a hole 38 in the flange 34.

The arm 32 may face either forward or to 75

the rear of the stock-feeding mechanism when the stock-guide member 25 is in the down or stock-guiding position, and whichever way the arm 32 faces for this position of the stock-guide member 25, the guide member 25 will be yieldable to retract upon interception of the pusher means for one direction of interception of the pusher means. In the form shown, the interception causing retraction of the guide member 25 occurs during a stock-feeding advance of the pusher means, and it will be understood that after such interception, the toggle and associated parts will be in the position shown by phantom outlines, as at 39.

To reset the mechanism, in other words to project the stock-guide member 25 into stock-guiding position, I prefer to employ means responsive to movement of the pusher means during another part of the cycle thereof; in the event that the machine is one in which bars of stock are automatically loaded, as after an automatic retraction of the pusher mechanism, then I prefer that the stock-guide means shall be projected downwardly upon an initial forward movement of the pusher means after stock-loading. In the form shown, an elongated toggle-reset rod 40 is pinned to the toggle mechanism at 36; rod 40 may extend rearwardly to the back end of the mechanism to derive its reset actuation. In the arrangement shown, rod 40 may not only follow the longitudinal movement of pin 36 during toggle actuation from one position to another, but it may also be raised and lowered, as suggested by the solid outline 40 and by the phantom outline 41 at the left side of Fig. 2; and a transversely bent projection or abutment 42 at the rear end of rod 40 may selectively cooperate with a first cam 43 fixed to the frame and a second cam 44 carried by part of the pusher means, as, for example, the forward carriage 17.

The cooperation of parts in a latch-resetting operation, that is, in an operation in which the stock-guide member 25 is projected into stock-guiding position, with be better understood from the description of a typical cycle of operations. Let it be assumed that the stock-guide means 25 is in the stock-guiding position, as shown in Figs. 2, 3, and 4, and the therefore at least an initial part of the stock has been fed into or consumed by the machine 10. With continued consumption of stock, the pusher means will advance until intercepted by the stock-guide means 25, and further advance would result in yieldable retraction of the member 25 to the position shown by phantom outlines 31-39. The toggle spring 33 will serve to retain this retracted position of the stock-guide member throughout the remainder of the stock feeding stroke, and even during retraction of the pusher means. All this time, that is, while the stock-guiding means is retracted, the latch-resetting bar 40 will have been projected rearwardly so as to ride down the surface of the fixed cam 43 and to be positioned in the path of the cam 44 as the pusher carriage 17 is retracted to the rear end of the mechanism. Just before reaching the rear end of the mechanism, the cam 44 will intercept the rod abutment 42, causing the rod abutment 42 to ride up and over the vertical abutment 45, which is carried with the pusher mechanism. The latch mechanism will then have been cocked, ready for resetting the stock-guide means 25. After loading a new piece of stock ahead of the pusher nose 20, the feeding mechanism will begin to advance the forward pusher carriage 17, and the latch or

other connection between the forward pusher carriage and the pusher nose 20 may be sufficiently strong to permit the abutment surface 45 on the forward carriage 17 to drive the abutment end 42 of rod 40 forward to actuate the toggle mechanism to the right and into the position shown (in solid outlines) in the drawings, with the stock-guide member 25 projected into stock-guiding relation with the newly loaded piece of stock.

In certain cases, speeds of rotation may be so high, or the stock may be of such small diameter with relation to its otherwise unsupported central span, that it may be desirable or necessary to provide more than one stock-guiding member, such as the member 25 which has been described; in Fig. 5, I show an arrangement wherein a plurality of longitudinally spaced stock-guide members 25-25' may be employed in guiding the central unsupported span of the stock whenever the unsupported span is sufficiently extensive to demand such support. In the arrangement of Fig. 5, the mechanism involving actuation of the guide member 25 may be exactly the same as that described in connection with Figs. 1 to 4, and the corresponding parts are therefore given the same reference numbers. As to the stock-guide member 25', it may be located longitudinally further toward the forward end of the stock-feeding mechanism than is the stock-guide member 25; it also may have a spring-toggle mechanism 33' and a pinned connection at 36' to an actuating rod 50. The rod 50 may be directly connected to the toggle mechanism for the rear stock-guiding means 25, but I prefer, and in the present form show, a lost-motion connection between these parts. The lost-motion mechanism may include an elongated sleeve 51, pinned at 52 to the rod 50, and a rod 53 may be directly connected to the rear toggle mechanism, as at the pin 36. The relationship of the parts is preferably such that with both toggles in the same relative position, there is substantially no lost motion between rods 50-53 and sleeve 51, in the relative direction in which said rods 50-53 may be urged toward each other.

In a typical sequence of operations involving the mechanism of Fig. 5, the stock-guide members 25-25' will have been projected downwardly at commencement of the feed stroke for the pusher means. When the pusher head intercepts the first or rear stock-guide member 25, the lost-motion connection with the forward stock-guide means 25' will permit automatic yielding retraction of the guide member 25 without disturbing the extended setting of the forward stock-guide member 25'. Upon continued progress of the stock-feeding means forwardly along the guide means 15, the second stock-guide member 25' will be intercepted, and the lost motion between stock-guide mechanisms will permit the independent yielding retraction of the stock-guide member 25'. Both stock-guide members 25-25' will remain retracted for the remainder of the feed stroke and may remain retracted for the entire retracting stroke of the pusher means. Upon loading a new piece of stock 12, and upon initial feeding of the stock-pusher means following loading, the abutment 44 on the forward pusher carriage may again actuate rod 40, and with it rods 50-53, to simultaneously downwardly project all stock-guiding members 25-25' into guiding relation with the stock 12.

It will be appreciated that I have described a relatively simple means for permitting stock

alignment for a maximum period of time during the feed stroke of a feed mechanism of the character indicated. This improved means may perform its aligning functions while the problem of aligning a large, unsupported central span of stock is most acute. My improved mechanism will be appreciated as being readily adaptable to existing feed mechanisms; its use may virtually eliminate excessive noise and damage or wear due to stock whip during high-speed spindle rotation.

While the invention has been described in considerable detail and preferred forms illustrated, it is to be understood that changes and modifications may be made within the scope of the invention as defined in the appended claims.

I claim:

1. A stock-feeding mechanism, comprising a frame including elongated guide means, stock-pusher means including guide means cooperating with said fixed elongated guide means, and a projectable and retractable stock-alignment guide member including a plurality of abutment members spaced with respect to the stock-pushing axis when said member is in an extended position, whereby when in said extended position, said member may maintain alignment of the stock on the stock-feeding axis, retraction means for said member comprising means responsive to a feeding advance of said pusher means, and projecting means for actuating said guide member from a retracted position to a projected position, said last-defined means including an actuating member movable upon movement of said pusher means during a part of the cycle of said pusher means and while said pusher means is in a substantially drawn-back position.

2. A mechanism according to claim 1, in which said retraction means includes a toggle mechanism having a first position to retain said stock-guide member in a projected position and a second position to retain said stock-guide member in a retracted position, whereby after an initial displacement of said means responsive to a feed of said pusher, said stock-guide member may be retracted with a snap action and held in retracted position.

3. In a stock-feeding mechanism of the character indicated, a frame including fixed elongated guide means, pusher means guided by said fixed elongated guide means and including a stock-engaging means supported on a stock-feeding axis, feed means for said pusher means including means for feeding and for retracting said pusher means in an automatic cycle, stock-guide means carried by said frame near the forward end thereof and including a guide member having a plurality of abutments about the stock-feeding axis when said member is in one position, said member being movable to a second position out of guiding engagement with stock being fed, means responsive to a movement of said pusher means in a first part of said cycle for projecting said stock-guide member into a stock-guiding position, and means responsive to displacement of said pusher means in another part of said feed cycle for retracting said stock-guide member out of the path of said pusher means.

4. In a stock-feeding mechanism of the character indicated, a frame including an elongated I-beam, fixed elongated guide means comprising spaced rails carried by one of the flanges of said I-beam, stock-pusher means including guide means cooperating with said fixed guide means and further including a revolute pusher head

on a stock-feeding axis for revolvably supporting one end of a piece of stock to be longitudinally fed, a guide fork pivotally carried by said frame between said rails at a forward location with respect to said fixed elongated guide means, said fork having fingers spaced on opposite sides of the stock-feeding axis for aligning engagement with a piece of stock to be fed, actuating means for said fork comprising an arm extending between flanges of said I-beam, a toggle spring resiliently connecting the upwardly projecting end of said arm with the other flange of said I-beam, said arm being to one side of the toggle dead-center when said fork is in a projected stock-guiding position, said arm being to the other side of the toggle dead-center when said fork is in a position retracted out of the path of said stock-pusher means, said fork being yieldable upon abutment with said pusher means for one direction of travel of said pusher means, and lost-motion means connecting said arm to said pusher means for actuation of said fork from a retracted position to an extended stock-guiding position in response to a movement of said pusher means when longitudinally remote from said fork.

5. A stock-feeding mechanism, comprising a frame including fixed elongated guide means, a stock-pusher member including guide means cooperating with said fixed guide means for guided movement therealong, said pusher means also including a head to engage a length of stock to be longitudinally fed, a plurality of longitudinally spaced stock-guide means retractably carried by said frame at locations spaced from the rear end of said fixed elongated guide means, said stock-guide means each including abutments spaced about the stock-feeding axis when in a projected or extended position, each of said stock-guide means being retractable out of the path of said pusher means, and separate resilient latch means for holding each of said stock-guide means in each of its two possible positions.

6. A mechanism according to claim 5, in which said stock-guide means are each independently yieldable to retract upon abutment with said stock-pusher means as the latter is fed forward, and interconnected latch-resetting means connecting said latches to each other and to said

stock-pusher means and responsive to a movement of said stock-pusher means when said stock-pusher means is at a location rearward of said stock-guide means for simultaneously projecting all said stock-guide means.

7. A mechanism according to claim 6, in which said latch-resetting means includes an actuating member in intercepting actuatable relation with said stock-pusher means only when said stock-pusher means is being fed forward and when said stock-pusher means is near the most rearwardly extended position of said stock-pusher means, whereby said mechanism may be loaded with a new length of stock before said stock-guide means are projected into stock-guiding position.

8. A stock-feeding mechanism, comprising a frame including fixed elongated guide means, stock-pusher means including guide means cooperating with said fixed elongated guide means, and a projectable and retractable stock-alignment guide member movably carried by said frame and projecting to directly embrace part of a length of stock for holding the same in axial alignment with said pusher means and with a machine to be fed, means responsive to a movement of said pusher means at a relatively forward position for retracting said guide member, and means responsive to a movement of said pusher means at a relatively drawn-back position for projecting said guide member into stock-guiding position.

9. A mechanism according to claim 8, in which said latching means includes an elongated rearwardly extending actuating bar, and one-way engaging latching means cooperating between said pusher means and the rear end of said bar.
